FEEDING DEVICE FOR ROCK DRILLS

Application filed January 24, 1930. Serial No. 423,066.

This invention relates to feeding devices, but more particularly to a device of this character adapted for actuating a rock drill relatively to its support, such as a shell whereon 5 rock drills of the drifter type are usually mounted to enable them to be readily advanced towards the work in accordance with the penetration of the drill steel into the material being drilled.

10 One object of the invention is to enable the rock drill to be moved longitudinally of its supporting shell by the force of the hammer piston upon reversal of said hammer piston at the end of one of its strokes and at the 15 same time to prevent recoil of the rock drill at the instant of such reversal.

Another object is to enable the rock drill to be readily actuated longitudinally of the shell either in the direction of the work or in 20 a reverse direction, and still another object is to enable the feeding device to be automatically reversed.

Other objects will be in part obvious and in part pointed out hereinafter.

25 In the accompanying drawing illustrating the invention and in which similar reference characters refer to similar parts,

Figure 1 is a longitudinal plan view, partly broken away, of a rock drill and its supporting shell having the invention applied thereto,

Figure 2 is a side elevation, partly in section, showing an enlarged view of the feeding device, the said feeding device being adjusted to the position for feeding the rock drill towards the work, and

Figure 3 is an end elevation of Figure 2 and partly in section illustrating the manner in which the movable elements of the feeding device may be locked in placed position.

Referring more particularly to the drawing, A designates a rock drill which may be of the drifter type, and B a supporting shell 45 for the rock drill A. The shell B has the usual guideways C to slidably receive ribs D carried by the cylinder E of the rock drill A.

The rock drill A has the usual front and back heads F and G which may be suitably

secured to the cylinder E by means of side rods H. The front head F acts as a guide for a working implement, such as a drill steel J, and within the cylinder E is a reciprocating hammer piston K to deliver blows of impact 55 against the working implement J for driving it into the work.

The pressure fluid utilized for actuating the piston K may be distributed to the ends of the cylinder E by any suitable form of distributing valve (not shown) and communication between the distributing valve and the source of pressure fluid supply may be controlled by a suitable throttle valve, only the manipulating lever L of which is shown. 60

In accordance with the present invention means are provided for enabling the rock drill A to be moved longitudinally of the shell B by the jar resulting upon reversal of the hammer piston K at the ends of its stroke. 65 As will be readily understood hammer pistons of this type travel at a high rate of speed so that upon the impact of the hammer piston against the working implement as well as when the piston reverses its direction of movement at the end of its return stroke a heavy jar is imparted to the rock drill tending to move it bodily in the direction in which the piston is traveling. 70

It is an object of this invention to utilize 75 such shocks or jars for actuating the entire rock drill longitudinally of the shell. The rock drill is accordingly provided with readily adjustable means which are adapted to intermittently seize and release the shell B 80 or elements fixedly secured thereto to prevent recoil of the rock drill when the piston reverses in one end of the cylinder, and to enable the rock drill to be moved along the shell by the jar resulting upon reversal of 85 the piston in the other end of the cylinder. 90

The stationary means associated with the shell B mentioned hereinbefore may consist of a rod O which is preferably disposed within the confines of the shell B and is seated with its forward end in a bearing plate P secured to the front end of the shell B by means of bolts Q. The rod O is preferably of cylindrical form and may be of such length that its rear end extends beyond the corre- 95 100

sponding end of the shell B. In structures wherein the length of the rod O exceeds that of the shell B the rear end of the rod O may be suitably supported by a cross head R which itself is supported by bolts S secured in any suitable manner to the rear end of the shell B.

Preferably the rod O is provided with a flange T to seat against the inner surface of the cross head R and the end U of the rod O which projects rearwardly of the cross head R is threaded to receive a nut V whereby the rod may be secured fixedly against end-wise movement. This arrangement also enables the position of the rod O to be readily changed whenever it is desired to present a new bearing surface for the element where-with the rod O is adapted to cooperate for advancing the rock drill A relatively to the shell B.

The element which cooperates with the rod O for shifting the position of the rock drill A in accordance with the penetration of the working implement J into the work consists of a link W which is pivoted on a bolt X supported by a bracket Y. The bracket Y may be in the form of a separate piece instead of making it an integral part of the rock drill A or portions thereof, and in this instance has a lateral flange Z which is seated against the back end of the back head G. In the flange Z are apertures b to accommodate the side rods H of the rock drill and whereby the bracket Y may be securely clamped to the back head G.

The link W is adapted to assume a lateral position with respect to the rod and has in its free end an aperture c through which the rod O extends and the aperture c is of somewhat larger diameter than the rod O so that the link W will be capable of some degree of oscillatory movement with respect to the rod.

The front and rear ends or edges of the aperture c constitute gripping edges d and e respectively which, when the link W occupies an inclined position, are adapted to grip the surface of the rod O for preventing recoil of the rock drill A depending upon the direction in which it is intended to actuate the rock drill and upon the direction in which the link W inclines.

Means are provided to hold the link W in the desired operative position and to urge the said link constantly in position to assure an immediate gripping action thereof on the rod O and thus avoid any tendency of the rock drill A to recoil upon the occurrence of a shock due to the reversal of the piston K in the cylinder E. The means provided for this purpose comprises a guide rod f which extends slidably through an aperture g in the link W and in this instance located intermediate the aperture c and the bolt X.

The guide rod f may be of suitable length to receive a pair of springs h and j which are

disposed forwardly and rearwardly respectively of the link W and against which they seat with their adjacent ends. On the rear end of the guide rod f is a head k against which the rear end of the spring j is adapted to bear, and on the front end of the guide rod f is threaded a nut o to form a seat for the front end of the spring h and also to vary the tension of the springs h and j.

In order to enable the link W to be manually adjusted to the various positions which it may assume as well as to selectively set up a tension in either of the springs h and j, the head k of the guide rod f is pivotally connected to a lever p which has a shaft q journaled in the bracket Y so that when the lever p is oscillated in one direction or the other, one of the springs h or j will be compressed to exert a yieldable pressure against the link W.

Fixedly secured to the shaft q is a controlling lever r having an integral grip portion s which may be grasped for actuating the lever p. In order to eliminate the necessity of constantly applying pressure to the lever r for the purpose of insuring the correct position of the link W, the grip portion s of the lever r is provided with a bore t to accommodate a spring pressed plunger u having a head v which is adapted to engage serrations w for locking the levers p and r in the desired operative position. The serrations w may be suitably formed in arcuate formation on the side of the bracket Y so that an ample contact between the head v of the plunger u and the said serrations will be assured.

The locking contact between the head v of the plunger u and the serrations is preferably such that the levers r and p will remain in position to hold one or the other of the springs h or j under compression unaffected by the vibrations incident to the operation of the drill A.

To the end that the link W may be automatically reversed from the position which it occupies during the time the drill is advancing toward the front end of the shell B to that which it assumes for reversing the travel of the drill, an adjustable abutment, designated generally by x, is provided to act against a lug y carried in this instance by the lever r.

The abutment x comprises a bearing z having a bore 2 therein to receive a plunger 3 which lies in the path of the lug y. The plunger 3 has a hollow head which lies within the bore 2 and a spring 4 seating with one end against one end of the bore 2 acts with its other end against the plunger 3 to hold said plunger in the rear end of the bore 2.

A convenient support is provided for the bearing z and said support comprises a main clamping member 5 which embraces the shell B and carries on one end hooks 6 which may

engage the edge of the shell B. In the opposite side of the clamping member 5 is disposed a shoe 7 which may be moved laterally of the shell B by means of a set screw 8 in the 5 clamping member 5. The shoe 7 may also be provided with a hooked portion 9 to overlie the edge of the shell adjacent to the shoe. This arrangement enables the clamping member 5, as well as the plunger, to be readily 10 adjusted along the length of the shell by merely manipulating the screw 8 to release the clamping hold on the shell after which the clamp together with the abutment may be readily shifted along the length of the shell.

15 The operation of the device is as follows: Let it be assumed that the rock drill A is in operation so that the hammer piston K delivers its blow to the working implement J to drive it into the material being drilled. 20 When the rock drill A is thus operating it is of course essential that the said rock drill be actuated longitudinally of the shell B in the direction of the work so that the full force of the hammer piston against the working implement J may be effective for driving the said working implement into the work.

In order to constantly assure this position of the percussive element of the drill with respect to the working implement J the levers 30 r and p may be rocked forwardly to cause the link W to assume a similar position. The spring j will thus be compressed so that it constantly tends to force the link W in the direction in which it is desired to move the 35 rock drill A. In this position of the link W the gripping edge e, which is the rear edge of the aperture e, will frictionally engage the surface of the rod O, and the link W will be maintained in this position as will also 40 the levers r and p by the plunger u which engages one of the serrations w.

With the rock drill in operation the jar caused by the hammer piston as it strikes the working implement J and by its act of reversal will be transmitted to the rock drill so that as the rock is being gradually reduced by the working implement the rock drill A will be carried forwardly bodily in the direction of the work. By its gripping action 45 upon the rod O the link W will prevent the rock drill from recoiling so that the rock drill will be held fixedly in position and the maximum effect of the blow of the hammer piston K against the working implement J will therefore be obtained. In the subsequent 50 operation of the rock drill this cycle will be repeated until the working implement J has penetrated the work to the desired depth. The link W will alternately grip and 55 release the rod O in such wise that any movement of the rock drill resulting from the jars of the piston K will only be in a forwardly direction since, when the piston K changes its direction of movement in the rear 60 end of the cylinder E, the rock drill will

be held against retrograde movement by the frictional engagement of the edge e with the rod O.

As the rock drill approaches the front end of the shell B the lug y will contact with the plunger 3. The spring 4 will then be compressed by the continued forward movement of the rock drill until the plunger strikes the front end of the bore 2 in the abutment z. Thereafter as the drill proceeds forwardly 75 the levers r and p will be gradually oscillated rearwardly, as will also be the guide rod f, thus releasing the compression in the spring j and placing the spring h under compression. This movement of the levers will, of course, 80 also be expedited somewhat by the force previously stored in the spring 4.

As will readily be seen, by changing the position of the levers r and p and by placing the spring h under compression the position 85 of the links W will also be reversed thus bringing the gripping edge d into a position to frictionally engage the rod O. Meanwhile the rock drill A will continue its operation, and with the link W in the new position the 90 gripping edge d will intermittently grip and release the rod O. Therefore, when the piston reverses its direction of movement in the front end of the cylinder E the gripping edge 95 d will prevent the rock drill from being carried forwardly, and at the end of the rearward stroke of the piston K the jar caused by the reversal of the piston will cause the rock drill A to be moved bodily in a rearwardly direction to return it to its initial position 100 preparatory to the drilling of a new hole.

In practice, the present invention has been found to be extremely efficient. This is largely due to the fact that the percussive element of the drill will always be in the proper position relatively to the drill steel so that the maximum effect of the blow thereto may be obtained, and also in part due to the fact that the drill is not subjected to a heavy pressure tending to drive it in the direction 105 of the work. The link merely holds the rock drill immovable to prevent recoil thereof during the reversal of the piston at the end of one stroke and allows the rock drill to be actuated along the shell during the reversal of the 110 piston at the end of the return stroke.

We claim:

1. In a feeding device, the combination of a support and a motor slidably supported by the support, a working implement, a hammer piston reciprocable in the motor to actuate the working implement and to move the motor longitudinally of the support, a rod supported by the support, a link carried by the motor to frictionally engage the rod for preventing recoil of the motor during the stroke of the piston in one direction and to release the rod during the opposite stroke of the piston, means for adjusting the position of the link to induce such movement of 120

125

130

the motor, a spring associated with the said means and acting against the link to maintain the link in frictional contact with the rod and separate pivots for the link and the adjusting means.

5 2. In a feeding device, the combination of a support and a motor slidably supported by the support, a working implement, a hammer piston reciprocable in the motor to actuate the working implement and to actuate the motor longitudinally of the support, a rod supported by the support, a link carried by the motor to frictionally engage the rod for preventing recoil of the motor, manually operable spring pressed means acting against the link to maintain said link in frictional engagement with the rod and means on the support forming an abutment for the spring pressed means to shift the link and thus cause the motor to move in a reverse direction.

10 3. In a feeding device, the combination of a support and a motor slidably supported by the support, a working implement, a hammer piston reciprocable in the motor to actuate the working implement and to actuate the motor longitudinally of the support, a rod supported by the support, a link carried by the motor to frictionally engage the rod for preventing recoil of the motor upon reversal of the piston at the end of one stroke and to release the rod upon reversal of the piston at the end of the opposite stroke, a guide rod extending slidably through the link, springs on the guide rod acting against the opposite sides of the link, a lever on the motor pivotally connected to the guide rod for adjusting the position of the link and to place one or the other of the springs under compression for urging the link into frictional engagement with the rod, a bearing adapted to be secured to the support, and a spring pressed plunger in the bearing to reverse the said means and the link, thereby enabling the motor to be actuated in a reverse direction by the piston.

15 4. In a feeding device, the combination of a support and a motor slidably supported by the support, a working implement, a hammer piston reciprocable in the motor to actuate the working implement and to actuate the motor longitudinally of the support, a rod supported by the support, a bracket carried by the motor, a link pivoted to the bracket and adapted to frictionally engage the rod, spring pressed means for urging the link into frictional contact with the rod, a lever pivotally connected to the bracket and to the said means for adjusting the position of the link to enable the motor to travel in either direction relatively to the support, serrations on the bracket, and a spring pressed plunger in the lever to engage the serrations for locking the link in the adjusted position.

20 5. In a feeding device, the combination of a support and a motor slidably supported thereby, a working implement, a hammer piston reciprocable in the motor to actuate

the working implement and to move the motor longitudinally of the support, a rod supported by the support, a link carried by the motor to frictionally engage the rod for preventing recoil of the motor upon reversal of the piston at the end of one stroke and to release the rod upon reversal of the piston at the end of the opposite stroke, a guide rod extending slidably through the link, springs on the guide rod acting against the opposite sides of the link, a lever on the motor pivotally connected to the guide rod for adjusting the position of the link and to place one or the other of the springs under compression for urging the link into frictional engagement with the rod, a bearing adapted to be secured to the support, and a spring pressed plunger in the bearing to reverse the said means and the link, thereby enabling the motor to be actuated in a reverse direction by the piston.

25 6. In a feeding device, the combination with a support and a percussive motor on the support and being subjected to jars incident to its operation tending to move the motor along the support, of recoil arresting means for the motor, and means on the support to shift the recoil arresting means for reversing the direction of movement of the motor relatively to the support.

30 In testimony whereof we have signed this specification.
